UNITED STATES PATENT OFFICE.

MARCUS CROHN, OF NEW YORK, N. Y.

SAFETY DEVICE FOR SCARF-PINS, STUDS, &c.

SPECIFICATION forming part of Letters Patent No. 737,356, dated August 25, 1903.

Application filed April 22, 1903. Serial No. 153,817. (No model.)

To all whom it may concern:

Be it known that I, MARCUS CROHN, a citizen of the United States, residing at Manhattan borough, New York city, in the county and State of New York, have invented new and useful Improvements in Safety Devices for Scarf-Pins, Studs, and other Articles, of which the following is a specification.

This invention relates to a device by which such articles as scarf-pins, hat-pins, studs, and the like can be secured against loss or theft. Such device can be made simple and cheap, and its features of construction are set forth in the following specification and claims, and illustrated in the annexed drawings, in which—

Figure 1 shows the fastening or safety device applied to a pin or shank. Fig. 2 is a sectional view of the safety device. Fig. 3 is a section as shown in Fig. 2 on a larger scale. Fig. 4 is a plan view of Fig. 3 sectioned along $\alpha\alpha$, Fig. 1. Fig. 5 is an end view of the slide in the clamp. Fig. 6 is a sectional view of the ball or clamp. Figs. 7, 8, and 9 are views corresponding, respectively, to Figs. 1, 3, and 4 and show a modification. Fig. 10 shows the modified form of the device applied to a stud or screw.

The safety device hereinafter described comprises in its make-up a clamp or body portion, which is ordinarily made in one piece, and a slide non-rotatively mounted thereupon, the said clamp or body portion being slotted to receive the slide to thereby positively prevent the rotation of the latter during its motion. In one form of the device the clamp or body portion is of ball form, while in the other it is tubular. In the case of the ball-shaped clamp it has a slot located diametrically opposite to a perforation therein through which the stem of the hereinbefore-mentioned slide passes. In the tubular form of the article the wall of the tube is slotted at diametrically opposite points to receive the slide.

The screw-stem a is provided with a head b and an eye c . The ball or other shaped clamp e has a slot f to receive the head b of the screw-stem and an opening g to receive the shank or pin h . A nut i engages with the screw-threaded portion of the screw-stem. A spring j is interposed between the nut and the said ball-clamp. The said spring, which surrounds

the screw-stem a , is inclosed by the shell or housing k , located between said clamp and nut. The screw-stem has a head, as shown, 55 and is received in the slotted part of the ball-clamp, and when engaged by the nut these parts will be locked together.

The clamp e need not necessarily be ball-shaped, but of any desired shape; but the 60 ball shape has been found practical. The clamp may be hollow or solid. The slide or stem a cannot turn in the clamp, but is slid one way or another as the nut i is rotated. By having the stem-head b flat and its seat in 65 the clamp of like shape the stem is kept from rotating even when the pin or shank h is drawn out. The head b is of such shape or size as not to slide out of the clamp in one direction. The spring j maintains a certain 70 hold or friction on the pin by the slide a , even if the nut is loosened, so that the device will not drop off the pin, although free to be moved back and forth until the nut is screwed home.

As previously indicated, the clamp need 75 not be ball-shaped, as shown by Figs. 1 to 6, inclusive. Upon reference to Figs. 7 to 10, inclusive, the clamp e' (illustrated in said figures) is of substantially cylindrical form, it having diametrically opposite slots f' in its 80 body to receive the head b' of the screw-stem a' . The head b' is of circular form, which is not the case of the head b . With the exception of the shape of the clamp e and the head b' the modified construction is exactly like 85 that hereinbefore described, and hence I employ the same characters to denote similar parts.

What I claim as new, and desire to secure by Letters Patent, is— 90

1. A safety device comprising a clamp or body portion of one piece, a slide non-rotatively mounted in the clamp, and an actuating-nut for the slide, the clamp and slide having eyes for the passage or reception of a pin 95 or other article.

2. A safety device comprising a clamp or body portion of one piece of material and having an eye for the reception of a pin or shank, a slide non-rotatively mounted in the clamp 100 and having an eye adapted to be brought into and out of register with the eye of the clamp, a nut for the slide, and a spring and sleeve between the nut and clamp.

3. A clamp or body portion having a seat for a slide, a headed slide non-rotatively mounted in the clamp, an actuating-nut for the slide and a spring and sleeve between the 5 nut and clamp, said slide and clamp having shank-receiving eyes.

4. A safety device comprising a clamp or body portion, a slide non-rotatively supported by the same, said clamp or body portion being 10 slotted to receive the slide to thereby positively prevent rotation of the latter, and an actuating-nut for the slide, the clamp and slide having eyes for the passage of a pin or other article.

5. A safety device comprising a ball-shaped 15 hollow clamp or body portion, a slide mounted in the clamp, the latter having a slot to receive the slide to thereby positively prevent rotation of said slide, and an actuating-nut for said slide, the latter and the clamp having 20 eyes for the passage of a pin or other article.

In testimony whereof I have hereunto set my hand in the presence of two subscribing witnesses.

MARCUS CROHN.
